UNITED STATES PATENT OFFICE.

FRED L. MACKENZIE, OF BEVERLY, MASSACHUSETTS, ASSIGNOR TO UNITED SHOE MACHINERY COMPANY, OF PATERSON, NEW JERSEY, A CORPORATION OF NEW JERSEY.

PROCESS OF MAKING NAIL-STRINGS.

1,241,868.

Specification of Letters Patent.

Patented Oct. 2, 1917.

Application filed October 14, 1914. Serial No. 866,675.

To all whom it may concern:

Be it known that I, FRED L. MACKENZIE, a citizen of the United States, residing at Beverly, in the county of Essex and State of Massachusetts, have invented certain Improvements in Processes of Making Nail-Strings, of which the following description, in connection with the accompanying drawings, is a specification, like reference characters on the drawings indicating like parts in the several figures.

This invention relates to fastenings and particularly fastenings of the type commonly termed "string nails."

String nails are used for the most part in shoe nailing or tacking machines and the ordinary nail string supplied for such machines comprises a series of nails formed in one integral string, usually with the point or end of the shank of one nail connected to some part of the head of the next nail. In use the nail string is carried upon a reel and the nailing machine is provided with a combined feeding and cutting tool which engages the head of the nail to be driven, feeds it into the throat of the machine, and severs it from the string. The mechanism of the machine for handling these nails is, therefore, very simple, and for many purposes it would be desirable to employ string nails if they could be manufactured economically, and could be provided with heads sufficient to prevent their being pulled through the parts which are to be secured together by them.

Up to the present time nail strings have been made by two processes or by a combination of these two processes, the first process consisting in successively pressing or swaging the nail form into a continuous strand of wire, and the second process consisting in punching or dieing the nail string out of a flat strip or ribbon. The first process is illustrated in the patent to L. Goddu, No. 190,575, May 8, 1877, and the second process is illustrated in the patent to G. Goddu, No. 641,099, January 9, 1900. A combination of these processes is shown in the patent to G. Goddu, No. 599,933, March 1, 1898.

When a string nail is formed by punching or dieing the nail out of a strip or ribbon, it is important, if the nail is to be used as a permanent fastening, that it have formed

thereon a considerable head projecting to 55 one or both sides of the shank in the plane of the strip, since it is obviously not possible without a swaging operation to cause the head to project over the flat sides of the nail shank. A nail of this type, having a considerable head, is shown in the patent to Dobyne, No. 1,058,661, April 8, 1913, and is manufactured, as shown and described in said patent, by removing from one side of a continuous ribbon pieces of such shape that 60 a string of nails may be formed, each having a distinct head and a distinct shank. The pieces removed from the ribbon are thrown away and therefore constitute waste in the 65 manufacture of the nail string.

An object of the present invention is an improved process of making nail strings, of the general type shown in said patent to Dobyne, by which the waste will be very materially reduced.

This and other objects and important aspects of the invention will appear from the following description and claims when considered in connection with the accompanying drawings, in which,—

Figure 1 illustrates my novel process of making nail strings, and shows a preferred form of nail string produced by it; and

Fig. 2 illustrates my novel process in connection with a somewhat different form of nail which may be produced by it.

In order to reduce the waste due to cutting out material from the strip or ribbon to form a nail having a distinct head and a distinct shank, the present invention contemplates the formation of two nail strings from a single strip or ribbon in such manner that the part of the material which would be cut out and thrown away in the formation of the head and shank, when making the 90 string from a ribbon of the width of the string, is now utilized in forming the head and a part of the shank of a nail upon the other nail string. By the improved process of this invention it has been found that the 95 saving in material, which would otherwise be thrown away, is as much as 66%.

In carrying out the process, the material removed to form the distinct heads and shanks of the nails in the strings is preferably removed from the two strips at a single operation. As shown in the drawings the outer straight edges of the ribbon or

strip are utilized as the straight edges of the nail strings, and the two strings are cut from the ribbon or strip in such manner that before being separated their heads overlap 5 with the strings extending in opposite directions.

The nail which constitutes the nail unit of the string shown in Fig. 1 comprises a shank 2 having a straight edge 4, which 10 is the edge of the ribbon or strip from which the nail string is cut, an inclined edge 6 and a head 8, which is hook shaped upon its under side, the downwardly projecting barb or point 10 of the head acting to increase 15 the holding power of the head, and being, preferably, beveled slightly at 11 upon its outer edge to compensate somewhat for the tendency of the curved inner edge to turn the point out in the driving operation. The 20 nail constituting the nail unit of the string shown in Fig. 2 likewise has a shank 2 having an outer straight edge 4 formed from the edge of the ribbon or strip from which the nail string is cut and an inclined edge 6, 25 the head 14 of this nail having parallel upper and lower edges 16 and 18 extending at substantially right angles to the edge 4.

In cutting the nail string from the ribbon or strip the material to be removed to form 30 the distinct head and shank of each nail is preferably punched from the strip, each punching removing this material from two opposed nails, as shown at 20 in Figs. 1 and 2, and the strings are then separated from 35 each other in the ribbon or strip by being sheared apart along the dotted line 22, Figs. 1 and 2. The punching and shearing operations may take place in succession or substantially simultaneously. Preferably, however, 40 the shearing operation follows the punching operation, the strip being punched in a step by step manner, and the shearing steps either alternating with the punching steps or being performed in a step by step 45 manner at a properly spaced interval from the point where the punching operation is being performed.

An inspection of either Fig. 1 or 2 will 50 make apparent the amount of saving effected by this process. By drawing a straight line from that side of the nail head which lies 55 within the strip to the corresponding side of the next nail head, the amount of material which would be cut off to form a corresponding nail string from a strip of the proper width to form a single string can 60 readily be determined, and the amount of this material can then be compared with the size of the punching 20 which is removed in forming the two strips, and at the same 65 time the amount of the ordinarily wasted material which is utilized in forming the head and a part of the shank of the opposed nail of the second nail string can also be determined. This is shown in Figs. 1 and 2.

The dotted line *a-c* shows the position of the edge of a strip from which a single nail string is to be formed. The waste per nail is indicated by the area *acef*. The waste per nail where my novel process is used is 70 one-half of the area *agf*, or one-half of the punching 20, which has been found, in the case of certain shapes of nails, to be only one-third of the former amount. It is thus seen that great economies are made possible 75 by my novel process. The novel string nail and nail string disclosed herein are claimed in a co-pending divisional application, Ser. No. 189,428, filed Sept. 4, 1917.

Having thus described my invention, what 80 I claim as new and desire to secure by Letters Patent of the United States is:—

1. That improvement in processes of making nail strings composed of nails having distinct heads and shanks, which consists in removing from a ribbon or strip of material pieces each having an outline corresponding to the area between opposed nails of the desired form arranged in opposed strings with the heads of one string 90 overlapping the heads of the other string, and separating the strip into two strings by cuts along lines corresponding to the lines of contact of opposed strings having the defined relation to each other. 95

2. That improvement in processes of making nail strings composed of nails having distinct heads and shanks, which consists in removing from a ribbon or strip of material pieces each having an outline corresponding to the area between opposed nails of the desired form arranged in opposed strings extending in opposite directions with the heads of one string overlapping the heads of the other string and in 105 contact, and separating the strip into two strings by cuts along lines corresponding to the lines of contact of opposed strings having the defined relation to each other. 100

3. That improvement in processes of making nail strings composed of nails having heads extending to one side of the shanks thereof, which consists in removing from a ribbon or strip of material pieces each having an outline corresponding to the area between opposed nails of the described form arranged in opposed strings extending in opposite directions, with the heads of one string overlapping the heads of the other string and having their end faces in contact 115 and having their side faces in contact with the shanks of the opposed nails, and then separating the heads from each other and from the shanks of the opposed nails. 120

4. That improvement in processes of 125 making nail strings composed of nails having heads extending to one side of the shanks and having projections extending from the under sides of the heads, which consists in removing from a ribbon or strip 130

of material pieces each having an outline corresponding to the area between opposed nails of the described form arranged in opposed strings extending in opposite directions, with the heads of one string overlapping the heads of the other string, and having their end faces in contact and having their side faces, including the side faces of the downward projections, in contact with the shanks of the opposed nails, and sepa-

rating the heads from each other and from the nail shanks.

In testimony whereof I have signed my name to this specification in the presence of two subscribing witnesses.

FRED L. MACKENZIE.
